UNITED STATES PATENT OFFICE

JOHN A. FERGUSON, OF PITTSBURGH, PENNSYLVANIA, ASSIGNOR OF ONE-THIRD TO
THOMAS B. STURGES, OF PITTSBURGH, PENNSYLVANIA

BUILDING UNIT AND SUPPORTING MEANS THEREFOR

Application filed October 2, 1928. Serial No. 309,805.

My invention relates to pre-cast building units, preferably made of cement, sand and aggregates, employed in the construction of ceilings and walls of a building, and particularly to means employed in conjunction therewith for attaching said units in place upon floor joists, beams, studding, or other suitable metallic members of structural frameworks.

10 The present invention contemplates the employment of pre-cast fireproofing units, as aforesaid, into which are moulded metallic supporting or attaching elements, designed to be used in connection with pins, keys, or locking elements for rigidly securing the said units to the structural framework; the construction being of such a character that when the locking keys or elements are inserted in place, the units will be drawn tight against 15 and supported upon the said structural members. The pre-cast units constructed in accordance with my invention are suitably reinforced throughout their length and breadth, according to accepted engineering principles 20 of design and construction, so as to resist all forces to which they may be subjected.

I am aware that, prior to my invention, supporting or unit attaching means have been employed in conjunction with pre-cast slabs, etc., for securing the pre-cast units to structural members of a building, but said means have always been a source of considerable trouble.

The prime object of the present invention 35 is to provide simple and efficient unit supporting and/or attaching means of such character as to provide rigid and properly positioned means for attaching the units to the flanged portions of beams, etc., in a simple and highly satisfactory manner.

It is a further object of the present invention to provide the units with means whereby they may be attached to any type of structural members and in various positions, that 45 is to say, vertical, horizontal, or inclined positions, and in such a manner as to ensure rigidity and resist all forces to which the said slabs or units may be subjected to in use.

In the accompanying drawings, which illustrate applications of my invention:

Fig. 1 is a perspective view of a ceiling construction embodying my invention;

Fig. 2, a detail sectional view showing a portion of the ceiling construction, the section being taken on line II-II of Fig. 1;

Fig. 3, a detail perspective view showing a form of metallic supporting element designed to be partially embedded in the slab or building unit;

Fig. 4, a part plan and a part sectional view of a ceiling construction showing a modified form of attaching means;

Fig. 5, a part elevational and a part sectional view, the section being taken on line V-V of Fig. 4; and

Fig. 6, a perspective view showing a modified form of metallic supporting element embodying my invention.

Referring to the drawings and as preferred, 5 designates a slab or unit formed of cement, sand and aggregates, and having embodied therein and extending longitudinally thereof, a plurality of metallic reinforcing members in the form of rods 6. In the form of my invention shown by Fig. 2, I employ 70 in conjunction with two of the reinforcing rods 6 of each unit, a unit supporting and/or attaching element designated generally by 7. This unit is particularly shown by the perspective view, Fig. 3, and, as shown, it comprises a body portion *a* having a locking element receiving opening *b*, two shelves *c* projecting from the body at substantially right angles thereto, and a depending apertured portion *d* having its opening *e* disposed in a plane below the plane of the shelves *c*. This supporting element 7 is formed of metal and is of such thickness as to provide a structure 80 possessing sufficient rigidity to enable locking elements to be employed in connection 85 therewith and be passed therethrough without bending, but, at the same time, it is sufficiently flexible to permit expansion and contraction of the units when they are attached to the beams, etc. of the framework.

These elements 7 are molded in the pre-cast unit and are designed to be connected with the rods 6, as particularly shown by Fig. 2. The openings *e* are of just sufficient diameter 90 to receive the rods 6. It will be noted that 100

a portion of each element 7 is embedded in the unit and a portion projects upwardly therefrom. The shelves c are so positioned that they will come into contact with the under face of the flange of the structural member, as illustrated, a beam 8; thus providing a metal-to-metal contact, which is very desirable at the points shown, as they provide efficient bearings for the units.

10 My invention is shown in connection with a ceiling construction and, as preferred, I employ in the framework of the building spaced-apart I-beams 8, and form the units 5 with a length sufficient to extend from the center of the base of one beam to the center of the base of an adjacent beam. The units are disposed below the bases of the beams and are designed to be carried therefrom by means of the supporting elements 7 cooperating with locking members 9, the latter being designed to be passed through the openings b and bear upon the upper faces of the units and upon the upper faces of the flanges of the I-beams.

25 The modified form of unit supporting element 7^a shown by Fig. 6 is quite similar to the form of Fig. 3, practically the only difference being that I provide the apertured depending portion d' with a ledge of shelf f projecting in an opposite direction from the shelves c'. The opening b' is also slightly different in configuration. This shelf f is positioned below the reinforcing rod to which the elements 7^a engage, and is designed to provide an additional reinforce for the unit, and at the same time is utilized for gauging its thickness.

30 In the ceiling construction shown by Figs. 4 and 5, I have shown the metallic body supporting element 7^b formed integral with a reinforcing rod 6^a. In this form of my invention, it will be noted that the rod 6^a adjacent its ends is bent upwardly and projects from the unit to form the looped element 7^b, and that a portion is returned into the unit body and extends thence to an end. This returned and longitudinally extending portion is designated g, and is particularly shown by Fig. 4. In this latter form of my invention, I preferably employ round pins 9^a for the locking members, said pins being adapted to be passed through the looped portion and, when positioned, to bear upon the top of the unit and the upper surface of the flange of the I-beam.

35 I claim:

1. A building unit comprising a pre-cast body having a reinforcing metallic member extending longitudinally thereof and embedded therein, a metallic body supporting element partially embedded in the body connected with the reinforcing member and projecting upwardly from said body, and a relatively short transversely extending locking member adapted to assume an inclined posi-

tion for cooperating with the supporting element for engaging the unit to a flanged structural member.

2. A building unit comprising a pre-cast body having a reinforcing metallic member extending longitudinally thereof and embedded therein, a metallic body supporting element partially embedded in the body and extending from the reinforcing member and projecting upwardly from said body, and a transversely extending locking member shorter than the body cooperating with the supporting element for engaging the unit to a flanged structural member, said supporting element being apertured, and said locking member entered in the aperture and adapted to make contact with the upper face of the unit and the flange of the structural member.

3. A building unit comprising a pre-cast body having a reinforcing rod extending longitudinally thereof and embedded therein, a body supporting element partially embedded in the body and threaded on said rod, said supporting element including a body portion provided with an opening therein, a depending apertured portion, and a shelf projecting from the body portion for engagement with a structural member.

4. A building unit comprising a pre-cast body having a reinforcing rod extending longitudinally thereof and embedded therein, a body supporting element partially embedded in the body and connected with said rod, said supporting element including a body portion provided with an opening therein, a depending apertured portion, and a shelf projecting from the body portion for engagement with a structural member, said shelf disposed in a plane between the planes of the openings in the body and depending portions and projecting from the body portion at substantially right angles thereto.

5. A building unit comprising a pre-cast body having a reinforcing rod extending longitudinally thereof and embedded therein, a body supporting element partially embedded in the body and connected with said rod, said supporting element including a body portion provided with an opening therein, a depending apertured portion, and a shelf projecting from the body portion substantially at the upper surface thereof for engagement with a structural member, said depending apertured portion also provided with a shelf below the aperture.

6. In a ceiling construction, the combination with flanged structural members, of pre-cast ceiling units each having a reinforcing metallic member extending longitudinally thereof and embedded therein, and having adjacent ends disposed beneath and in engagement with a structural member, a metallic unit supporting element connected with the reinforcing member and projecting from

the unit, said element having a portion in contact with a face of one of the structural members and an apertured portion above the contacting portion, and a locking element 5 passed through the apertured portion and contacting with the unit between said structural members and the flange of one of the structural members.

In testimony whereof I affix my signature.
